UNITED STATES PATENT OFFICE.

DOUGLASS L. ARNOLD, OF CHICAGO, ILLINOIS, ASSIGNOR TO INTERNATIONAL HARVESTER COMPANY, A CORPORATION OF NEW JERSEY.

INTERNAL-COMBUSTION ENGINE.

Application filed June 25, 1919. Serial No. 306,665.

To all whom it may concern:

Be it known that I, DOUGLASS L. ARNOLD, a citizen of the United States, residing at Chicago, in the county of Cook and State 5 of Illinois, have invented certain new and useful Improvements in Internal-Combustion Engines, of which the following is a full, clear, and exact specification.

This invention relates to engines, and 10 especially to the inlet passages and construction of a cylinder head.

The walls of the inlet passages are, as a rule, relatively cool, and where fuel oils of a low grade, such as kerosene, are used 15 there is a great tendency for these oils to recondense on the walls of the inlet passages and to be carried over by the air into the cylinder in a liquid state.

It is an object, therefore, of my invention 20 to provide a means for revaporizing the condensed fuel, delivering it to the cylinder in the form of a dry, combustible gas.

Another object is to provide a means for 25 more perfectly mixing the air and fuel so as to avoid stratification and to obtain a more homogeneous combustible mixture.

Another object is to provide a means for 30 using the waste heat of the exhaust and of the cylinder to accomplish the above objects.

Still another object is to provide a means 35 for bringing any particles of unvaporized fuel into contact with the hot portions only of the intake walls, thereby using the liquid fuel itself as an insulator for the incoming charge, preventing said charge being heated with a consequent loss of volumetric efficiency 40 of the engine and at the same time allowing the liquid fuel to be vaporized and to enter the cylinder as a dry, hot gas, or in such unstable liquid form that the additional heat of compression gasifies or so changes 45 said fuel that it is in the proper state for good combustion. The amount of the charge heated in this case is so small as not to materially affect the volumetric efficiency of the engine.

These and other objects are accomplished 50 by my invention which comprises an internal combustion engine having an inlet valve and a tangential inlet passage formed about said inlet valve as a center so as to subject the incoming charge to vortex action at said valve.

In another aspect my invention comprises 55 a spiral inlet passage, as I have just stated,

and means for heating a part of the walls of said spiral inlet passage.

Referring now to the drawing—

Fig. 1 is a horizontal sectional view on the line A—B of Fig. 2; and

Fig. 2 is a front elevation, partly in section, on line C—D of Fig. 1.

I have illustrated my invention in connection with an engine having a cylinder 10, on which is secured a cylinder head 65 casing 11 by means of studs 12 and nuts 13. The cylinder head has cast therein exhaust passages 14 which are preferably shown at the two ends of the twin cylinders, while the inlet passage 15 having tangential 70 branches 15^a is shown between. It will be noted that at the heart, shown by double section lines, the inlet and exhaust passages are separated only by a thin wall of metal 15^b. The tangential inlet terminates in an 75 inlet port 16 which is closed by the inlet valve 17 which is held upon its seat by a spring 18.

The spiral passage 15^a is so arranged that as the incoming gases flow around this passage they are constantly brought nearer and nearer the inlet port 16, until at the point 15^c the wall of the tangential passage practically coincides with the edge of the inlet port. The exhaust port 19 is closed by 85 an exhaust valve 20 which is held upon its seat by a spring 21. It will be seen from the drawing and description that as the mixture going through the passage 15 strikes an abutment 15^d, it causes the gas 90 to turn first to one inlet port 16 and then to the other as they are alternately opened by lifting the valves 17, and as it is turned the mixture of air and liquid fuel is forced through the spiral passage 15^a. The result 95 of this spiral action is to throw towards the outer edge any heavier particles, such as condensed fuel, and to bring them violently in contact with the outer wall 15^b of the spiral passage, thereby depositing the fuel 100 on this wall. This wall, however, is heated by the exhaust gases in the exhaust passage 14.

At the same time, any fuel which falls to the bottom of the tangential passage 15^a 105 will come in contact with the heated head 22 of the cylinder itself, and any fuel therefore which comes in contact with the bottom of the passage 15^a or the hot spot 15^b will be converted into a dry, hot gas or in such 110

unstable liquid form that when it is passed on into the cylinder the additional heat of compression gasifies or so changes said fuel that it is in proper state for good combustion. 5 If, however, as is usually the case, some of the heavy fuel still clings to the wall of the tangential passage after having passed the hot spot 15^b this fuel will be thrown in the form of a very fine spray off the tip 15^c and 10 will be carried into the center of the vortex and will pass into the cylinder in a very finely divided unstable state. The result is that with this arrangement of elements I am able to get a very good combustible mixture. 15 It will be seen from the cross sectional view, shown in Fig. 2, that the intake passage 15 and the passage leading to the inlet port 16 are comparatively shallow, that is to say, a cross section of 20 these passages is substantially rectangular in shape. This rectangular shape, together with the volute shape of the intake passage positioned adjacent the intake valve 17, will cause a better mixing of the air 25 and fuel. It is also to be noted that the inlet passages are water-jacketed with the exception of the hot spot 15^b and the bottom wall 22 which forms the cylinder head of the engine and is directly exposed to the heat of 30 combustion in the cylinder. I have found it advantageous in some instances, but not essential to efficient operation of the engine, to have this lower wall heated as shown. With this construction, any liquid fuel which 35 may tend to settle to the bottom of the passages will be vaporized by the heat from the cylinder and at the same time serve to insulate the air and lighter components of the charge from the heated surface.

40 While I have shown and described but a

single embodiment of my invention, it is to be understood that it is capable of many modifications. Changes, therefore, in the construction and arrangement may be made without departing from the spirit and scope 45 of the invention, as defined by the appended claims.

I claim—

1. In an internal combustion engine, a cylinder having an inlet port, a volute inlet 50 passage in the cylinder leading to the inlet port and having its outer wall terminating tangent to the port.

2. In an internal combustion engine, a cylinder having an inlet port, a volute inlet 55 passage of uniformly decreasing radius formed in the cylinder leading to the port and its outer wall terminating tangent thereto, and an exhaust passage in the cylinder separated from the inlet passage by a thin 60 partition.

3. In an internal combustion engine, a cylinder head having an inlet port, an inlet 65 passage in the cylinder head, an eccentric inlet chamber tangent to the inlet port on one side and communicating with the inlet passage, the wall of the chamber terminating in a sharp edge at the point of tangency.

4. In an internal combustion engine, a cylinder head having an inlet port, an inlet 70 passage in the cylinder head, an eccentric inlet chamber tangent to the inlet port on one side and communicating with the inlet passage, the wall of the chamber terminating in a sharp edge at the point of tangency, and 75 means for heating a wall of the eccentric chamber.

In testimony whereof I affix my signature.

DOUGLASS L. ARNOLD.
